HEAT EXCHANGE STRUCTURE

James G. Van Vleet, Kenmore, N. Y., assignor to
The Linde Air Products Company, a corporation
of Ohio

Application July 18, 1940, Serial No. 346,118

5 Claims. (Cl. 257—236)

This invention relates to structures comprising helically finned tubes or tubing, and more particularly to improved heat exchangers employing such tubes.

One of the most efficient agencies for bringing about the transfer of heat between bodies of fluid is a tube or duct, provided with extended heat transfer surface in the form of a helically wound ribbon or fin which may be either integral with or attached to the exterior of the tube. While various types of flow arrangement may be employed for the transfer of heat between bodies of fluid flowing in heat exchanging relationship, if the transfer of heat is effected through the agency of finned tubes, one of the fluids ordinarily flows inside the tubes while another fluid is passed or repassed transversely across the tube in a direction generally parallel to the surfaces of the fins. Where more than one fluid is passed, or the same fluid is repassed, across a tube, or a bank of tubes, it is important to control, with more or less precision, the direction of flow of fluid across the tubes, to confine the fluid to a desired zone and to prevent leakage or escape of fluid from one zone to another, all as required according to a number of factors. For this purpose, baffles or partitions extending transversely of the tubes have been commonly employed. Furthermore, it is essential that tubes of substantial length be supported between their ends to avoid sagging, and in certain types of uses excessive vibration.

Heretofore the use of transverse baffles with helically finned tubing has been found impracticable or attended with disadvantages and objections. Methods for the fabrication of structures comprising finned tubing in combination with baffles or supports through which the tubes pass have been expensive, and structures containing such baffles or supports for finned tubes have heretofore been characterized by certain disadvantages and objections including, for example, reduced efficiency due to removal or wearing away of the fins by the supports or baffles due to vibration of the tubes, and leakage of fluid past the baffles or supports.

Among the objects of the present invention are: the provision of improved structures comprising helically finned tubes or tubing in combination with plates or sheets extending transversely of such tubing and serving as baffles or supports for the tubing; and the provision of improved heat exchangers employing helically finned tubes.

Still another object is to provide a heat ex-

change vessel of improved structure and efficiency which is particularly adapted for the countercurrent exchange of heat between high pressure air and one of the constituents of air in processes for the rectification of air involving compression and liquefaction.

For a fuller understanding of the nature and objects of the invention, reference should be had to the following detailed description taken in conjunction with the accompanying drawings, in which:

Figure 1 is a side elevational view, partly in section, of a shell and tube heat exchanging structure embodying the principles of the invention;

Figure 2 is a section taken along the line 2—2 of Figure 1, the tubes not being shown;

Figure 3 is an enlarged detailed view showing the arrangement of helically finned tubing with a transversely extending baffle or support, the view being partly in section along the line 3—3 of Figure 4.

Figure 4 is an enlarged detailed view, partially in section, showing one arrangement of a plurality of tubes extending through a baffle or support;

Figure 5 is a side elevational view showing a modified form of heat exchange structure embodying the principles of the invention.

Figures 6, 7, 8, 9, and 10 are details of modifications of the invention described hereinafter.

Figure 11 is an elevation of an arrangement modified from that shown in Figure 5.

Referring to Figures 1 and 2, the form of apparatus shown therein is a heat exchange vessel E of the shell and tube type, comprising a shell 11, helically finned tubes 12, and tube sheets 13, 13. The shell 11 is provided with an inlet 14 and an outlet 15 for fluid flowing through the shell in heat exchanging relationship with the exterior surfaces of the tubes 12. Headers 16, 17 are for the purpose of distributing fluid for flow through the tubes 12, and for collecting the fluid after it has traversed the tubes.

Within the shell 11 are provided a number of flanged sheets or flanged plates 18 which serve both as supports for the tubes 12 and as baffles for directing the flow of fluid through the shell 11. As shown in Figure 3, the tubes 12 are provided with helical fins 19 for substantially the entire length of the tubes within the shell. The helical fins of the finned tubes may be formed of ribbons or narrow strips of metal which are attached in good thermal contact to the walls of the tube, as by welding, soldering, brazing and

the like, or the fins may be formed integral with the tubes.

Each flanged sheet or plate 18 serving as a baffle or support for the tubes is provided with a tube receiving aperture or apertures 21, which in each sheet correspond to the tubes in number. The aperture 21 includes a circular part 22 having a diameter corresponding to the root diameter of the finned tubing and a radially extending slot 23 of a length in a radial direction such that the radius of the circular part 22 plus the length of the slot 23 corresponds to but is slightly in excess of the outside or external radius of the finned tubes. By root diameter of the finned tube is here meant the outside diameter of the tubing itself. The circular part 22 of the opening 21 should be slightly larger than the root diameter of the finned tubes but preferably only to the extent that may be necessary for convenience in assembling the structure. On the other hand, it is desirable that the finned tube fit as snugly as possible in the aperture 21 for the purpose of more firmly supporting the tubing by the plate and to minimize leakage between the plate and the tube. In any event, however, the tube receiving aperture 21 in the plate 18 should be smaller than the transverse section of the finned tubing. By transverse section of the finned tubing is meant the area to the outside diameter of the tube including the fin, taken transversely of the longitudinal axis.

The thickness of the sheet or plate, or at least that part thereof, immediately adjacent the aperture 21, is so limited that the plate may be accommodated or positioned between adjacent turns of the fins. The slot 23 should be of such a width between the edges thereof as to accommodate the pitch of the fin with the edges of the slot substantially in contact with the fin to minimize leakage between the fin and the sheet. If desired, the edges of the slot may be bent or flared slightly in the direction of the pitch to permit the use of a narrower slot, or the walls of the slot may be helical. A modification of the invention in which the edges 54 of the slot 53 are bent or flared is illustrated in Figures 6, 7 and 8. Another modification of the invention in which the walls 64 of the slot 63 are helical is shown in Figures 9 and 10.

Thus it is seen that the helically finned tubes 12 may be screwed and secured into plates or sheets 18 provided with apertures 21. In order to be able to screw the finned tubes 12 into a number of plates or baffles as shown in Figure 1, it is essential that the centers of the circular part 22 of the apertures 21 for a given tube be substantially in alignment with the longitudinal axis of that tube for all such plates.

In assembling the shell and tube type structure, the sheets 18 may first be placed within the shell 11 and properly positioned and spaced by spacers 24. With the apertures 21 in substantial alignment, the tubes may be screwed through the baffles and longitudinally positioned within the shell 11 beginning at either end of the shell. The shell may then be closed in the usual fashion by the tube sheets 13, 13. The connections between the headers 16 and 17 and the tubes 12 may also be made in the customary manner after the tubes 12 have been mounted in the tube sheets.

As shown in Figure 1, the plates 18 which are segments of a circle having a diameter substantially the same as the inside diameter of the shell 11, are so positioned relatively to one an-

other as to cause fluid flowing in the shell 11 to traverse a sinuous path between the inlet 14 and the outlet 15. The fluid is thus caused to pass and repass across the finned tubes 12 in a direction substantially parallel to the surface of the fins. Spacers 24 and tie bolts 25 extending axially of the shell 11 additionally assist in spacing and supporting sheets or plates 18. The tie bolts also assist in holding the tube sheets 13 against the ends of the shell 11. Additional reinforcement of the tube sheets 13 may be provided by the tubes 12, the unfinned ends of which may be sealed to the tube sheets as by welding, soldering, brazing and the like, or by expanding the tubes into the openings in the tube sheet.

A wide variety of patterns and arrangements of helically finned tubing in combination with sheets and plates serving as baffles and supports can be employed in accordance with the principles of the invention to suit particular requirements. Such heat exchangers are not only more rugged in structure but also more efficient. Leakage through the baffles at the openings where the finned tubes pass therethrough is unusually small.

Referring to Figure 5, the form of apparatus shown therein comprises a heat exchange structure of the so-called surface cooler type embodying the principles of the invention. It comprises helically finned tubes 31, 32, 33, 34 and 35 in combination with substantially parallel sheets 36, 37 and 38, which plates serve as supports for the tubes and may also serve as guiding elements or baffles for fluid flowing transversely across the finned tubes.

Each of tubes 31, 32, 33 and 34 is provided with unfinned ends 41, 42, 43 and 44, respectively, which unfinned ends are reversely bent through an angle of about 180 degrees relatively to the longitudinal axis of the remaining finned part of the tube; each reversely bent end is bent to such a radius that it is adapted to serve as a return bend in an assembly of finned tubes forming a heat exchange structure. End sheets 36 and 38, and intermediately positioned sheet 37, are each provided with apertures of the type shown in Figures 3 and 4. The apertures in the several sheets are so aligned with respect to one another that tubes 31, 32, 33, 34 and 35 can be screwed through the sheets to provide the structure illustrated in Figure 5. Tube 35 which is a terminal tube without a reversely bent end, may be screwed into the plates beginning at either end plate 36 or 38. Tubes 31 and 33 are screwed into the sheets beginning at end sheet 36, and tubes 32 and 34 are screwed into the sheets beginning at end sheet 38, with tube 32 being positioned intermediately of tubes 31 and 33. When each of tubes 31, 33 and 32, 34, all of which are of substantially the same length, have been screwed into end sheets 36 and 38 for practically the entire finned part of the tube, the position of the reversely bent ends 41, 42, 43 and 44 are adjusted to bring them into alignment with the longitudinal axes of tubes 32, 33, 34 and 35, respectively.

Because the reversely bent ends of tubes 31, 32, 33, and 34 are bent to such a radius as adapts them to serve as return bends, as described above, (or, conversely, the aligned openings spaced from one another according to the radius of the return bends) each reversely bent end may be brought into substantial proximity and alignment with the straight or unbent end

of an adjacent tube by turning the corresponding tubes in a clockwise or counterclockwise direction. The final adjustment may be made by cutting, trimming or building up the ends of the tubes, if necessary, and the tubes joined, as by welding, brazing, soldering and the like, to form a continuous path for flow of fluid therethrough.

In Fig. 11 there is shown a heat-exchange structure of the so-called surface cooler type very similar to the structure of Fig. 5 in its fundamentals. For greater efficiency of heat exchange, however, the finned tubes 72 in Fig. 5 are spaced so closely together, and the helical fins have such an outside diameter that the tips of the fins of adjacent tubes barely clear one another, thus substantially eliminating the open flow area between adjacent tubes found in ordinary structures.

It is not essential that the aligned openings for a number of tubes of a heat exchange structure be so spaced, relative to one another, that the tubes positioned therein are parallel. If desired, the aligned openings for the tubes may be so spaced that the tubes are non-parallel. In a heat exchange structure having tubes which are substantially horizontal or at a small angle to the horizontal, a non-parallel arrangement of tubes in series flow is of advantage where it is desired to provide a pitch to the tubes for the fall of fluid flowing therethrough.

It is not essential that the slots for the fins be cut at the bottom of the circular part of the aperture, as shown in Figure 2 for instance. In structures in which the tubes extend substantially horizontally, it may be advantageous to cut the slot for the fin at a place above the bottom of the circular part of the opening in order to provide the best support for the tubes and to insure that the weight of the tube is not carried on the corners of the slot or on the edge of the fin.

The form of heat exchange structure illustrated in Figure 1 is particularly suited for the countercurrent exchange of heat between warm high pressure air and cool nitrogen gas in processes for the separation of air into two or more of its constituents. In such processes the high pressure air may be admitted to one of the warm high pressure air heaters, say 17 in Figure 1 and, as it flows through the tubes or conduits 12, it is cooled by countercurrent heat exchange with cold nitrogen which may be admitted to the shell 11 through the inlet 14 and be discharged from the shell at the outlet 15. Although the passes of nitrogen across the tubes 12 in the passages defined by the plates 18 are essentially cross flow rather than counter flow, nevertheless, the overall result very closely approximates a true countercurrent heat exchange relationship by the use of an appropriate number of baffles and passes.

One important reason for the high efficiency which it is possible to attain with heat exchange structures made in accordance with the present invention is that the finned tubes (12 in Figure 1 or 72 in Figure 11) can be placed more closely together than would be the case if the openings 22 were made as large as the outside diameter of the fins. In the latter case, adjacent tubes would ordinarily be spaced so far apart that an

open flow space or area outside the fins would result. Thus, in accordance with the present invention a greater heat transfer surface can be provided per unit space while at the same time leaving ample metal in the baffle or plate to provide adequate strength for support even with very close spacing of the apertures. It has been found that a very desirable arrangement is one in which the tubes are so closely spaced that the tips of the fins of one tube barely clear the tips of the fins of an adjacent tube or tubes.

The forms of invention here described and illustrated in the accompanying drawings by way of examples are disclosed to indicate how the invention may be applied. Other forms which may differ more or less in detail without differing in principle, however, will suggest themselves to those skilled in the art.

I claim:

1. An apparatus comprising, in combination, a helically finned tube and a sheet extending transversely of said tube and being positioned intermediate of adjacent turns of the fin of said tube; said sheet being provided with an aperture for said tube smaller than the transverse section of such finned tube, said aperture including a circular part having a diameter at least as great as the root diameter of the finned tube and a radially extending slot having a length in a radial direction such that the radius of said circular part plus the length of said slot is at least as great as the external radius of the finned tube; and said sheet being of a thickness, at least in the area immediately adjacent said aperture, to be accommodated between said adjacent turns of the fin.

2. An apparatus as defined in claim 1 wherein the slot is of such a width as to barely accommodate the fin therebetween, with the edges of said slot substantially in contact with the surfaces of said fin, whereby to minimize leakage between said fin and said sheet.

3. An apparatus as defined in claim 1 wherein the edges of said slot are bent or flared in the direction of the pitch of the fin.

4. An apparatus as defined in claim 1 wherein the walls of said slot are helical, conforming substantially to the pitch of said fin.

5. An apparatus comprising in combination a plurality of helically finned tubes and a sheet extending transversely of said tubes and being positioned intermediate of adjacent turns of the fins of each of said tubes; said sheet being provided with apertures for said tubes smaller than the transverse section of such finned tubes, each of said apertures including a circular part having a diameter at least as great as the root diameter of the finned tubes and a radially extending slot having a length in a radial direction such that the radius of such circular part plus the length of said slot is at least as great as the external radius of the finned tubes; said apertures being so closely spaced relative to one another that the tips of the fins of adjacent tubes barely clear one another; and said sheet being of a thickness, at least in the areas immediately adjacent said apertures, to be accommodated between said adjacent turns of the fins.

JAMES G. VAN VLEET.
